UNITED STATES PATENT OFFICE

EARL R. SWANSON, OF CHICAGO, ILLINOIS, ASSIGNOR TO CHICAGO-CLEVELAND CAB ROOFING COMPANY, OF CHICAGO, ILLINOIS, A CORPORATION OF DELAWARE

CAR ROOF

Application filed May 6, 1929. Serial No. 360,837.

My invention relates to roofs for railway cars and more particularly to steel roofs therefor comprising a plurality of metal sheets associated with a car superstructure of metal carlines.

5 The principal object of the invention is to so construct a roof of this type that it may be efficiently insulated.

A primary feature of the invention consists in providing a car roof of the type involving a plurality of carlines and roof sheets disposed therebetween, with insulating material spanning the spaces between the carlines in engagement with the undersides of the roof sheets.

10 Another feature of the invention resides in providing a car roof of the type involving a plurality of carlines and roof sheets spanning the spaces between the carlines, with sheets of insulating material respectively interposed between the carlines and underlying the roof sheets, said roof sheets being supported by the carlines through the intermediacy of the insulating sheets.

15 A further feature of the invention consists in providing a car roof of the type involving a plurality of carlines having roof sheets spanning the spaces between them, with sheets of insulating material interposed between and supported by the carlines and underlying the roof sheets, and with additional sheets of insulating material underlying the carlines and extending substantially continuously from one side of the car to the other.

20 A still further feature of the invention resides in associating with a car roof of the type having a plurality of carlines each provided with laterally projecting flanges, sheets of insulating material respectively interposed between the carlines and supported by the lateral flanges thereof and roof sheets overlying and supported by said insulating sheets.

25 Other and more specific features of the invention residing in advantageous forms and

combinations of parts will hereinafter appear and be pointed out in the claims.

In the drawings illustrating preferred embodiments of the invention:

Figure 1 is a fragmentary plan view of a 50 car roof embodying my invention, portions of the roof sheets being broken away.

Figure 2 is a longitudinal sectional view taken on line 2—2, Figure 1.

Figure 3 is a fragmentary enlarged sectional view taken on line 3—3, Figure 1.

Figure 4 is a fragmentary enlarged sectional view taken on line 4—4, Figure 1.

Figure 5 is a fragmentary view similar to Figure 4 illustrating the modified form of 60 the invention.

Figure 6 is a sectional view similar to Figure 4 illustrating a still further modified form of the invention.

Referring more particularly to the drawings 1 indicates the side plates of the car roof frame, each of which is preferably Z-shaped having a substantially vertical web 2 and oppositely projecting horizontal flanges 3 and 4, respectively. Extending transversely of the car are a plurality of inverted substantially channel-shaped carlines 5, each being advantageously fashioned with a top web portion 6 and downwardly diverging sides 7 which terminate in laterally projecting base 75 flanges 8. At their opposite ends the carlines rest upon and are secured to the inwardly projecting horizontal flanges 3 of the side plates 1 by any suitable means.

Spanning the spaces between the carlines and preferably extending continuously from one side plate to the other are a plurality of roof sheets 9. For supporting the eaves' edges of the roof sheets wooden fillers 10 may be conveniently interposed between them and the horizontal flanges 3 of the side plates, the wooden fillers being secured to the side plates by bolts 11.

Adjacent their marginal edges each of the roof sheets is offset as at 12 and terminates

short of the respective sides of the cooperating carlines in upwardly projecting flanged portions 13. Embracing each of the carlines is a substantially trough-shaped seam cap 14 which, if desired, may extend continuously from one eaves' edge of the car to the opposite one. Each of the seam caps is formed with a web portion 15 and downwardly diverging sides 16 which are respectively in continuous contact with the web and sides of the carlines for substantially the entire length of the latter. The lower portions of the sides of the seam caps are bent as at 17 to form housings for the upstanding flanges of the cooperating roof sheets and are re-flanged as at 18 for engagement with the offset portions 12 of the roof sheets. The flanges 18 of the seam caps and the offset portions 12 of the roof are so formed and related that when the seam caps are secured in place the flanges 18 thereof exert a downward pressure upon the roof sheets. A plurality of clamps 19 are employed for rigidly securing the seam caps 14 to the carlines. Each clamp is fashioned with downwardly diverging sides 21, the divergence of the sides of the clamps normally being somewhat less than the divergence of the sides of the carlines so that when the clamps are drawn downwardly the sides of the seam caps are forced into wedging engagement with the sides of the clamps. In the preferred embodiment of the invention each of the clamps is shown as being provided with a bolt 22 which depends downwardly from the web thereof through an aperture formed in the web 6 of the carline. Disposed within each of the carlines are a plurality of wooden fillers 23 respectively adjacent the clamps 19 which are apertured to receive the bolts 22 of the latter. The portion of each of the filler blocks 23 adjacent the end of the bolt of the associated clamp is cut away as at 24 to form a recess for receiving a nut 25 having threaded engagement with the lower end of the bolt. Another means for securing the clamps in place is illustrated in Figure 6 of the drawings. In this case each of the clamps is provided with a depending bolt 26 provided with an elongated slot for receiving a wedge key 27. The key is formed so that after it has been driven into place its ends may be spread apart to prevent it from being accidentally displaced from cooperative association with the clamp.

In order to prevent sudden changes of temperature within the car and to maintain a somewhat even temperature therein insulating material is interposed between the carlines and roof sheets on the one hand and the inside of the car on the other. The insulating material is preferably formed in sheets 28 and 29 and may be of any suitable material such as celotex, beaver board or their equivalent. A sheet

of this material is interposed between each of the carlines and preferably extends continuously therebetween and between the side plates in engagement with the underside of the associated roof sheet. The side marginal edges of the insulating sheets 28 overlapingly engage and rest upon the lateral base flanges 8 of the carlines. The insulating sheets 28 are made so as to possess sufficient stiffness and rigidity to form, with the exception of the fillers 10, the sole support for the roof sheets 9. In this manner the usual purlins and ridge pole of the car roof construction may be eliminated. The sheets 28 are clamped between the lateral base flanges 80 of the carlines and the roof sheets by the downward pressure exerted on the roof sheets by the seam caps 14. When a relatively soft or porous type of insulation is used the compression thereof may be limited by interposing fillers 30 between the lateral flanges of the carlines and the offset portions 12 of the roof sheets as clearly shown in Figure 5. It will, of course, be appreciated that although the insulation may be relatively soft or porous it will still have sufficient rigidity to support the roof sheets.

The undersides of the carlines are insulated by the sheets 29 which are of a width substantially equal to the base of the carlines and which extend preferably continuously from one side plate to the other. These insulating sheets engage the undersides of the lateral base flanges of the carlines and are preferably secured in place by any suitable means such as nails 31 which pass through the insulation into the filler blocks 23 within the carlines. A nailing strip 32 may advantageously be employed to prevent the securing nails 31 from tearing or otherwise injuring the insulating sheets 29 and thereby enable the sheets to move out of engagement with the undersides of the carlines.

Figure 6 illustrates a manner in which the insulating sheets 28 and 29 may be supported when a securing clamp of the type illustrated therein is employed. As clearly shown, the insulating sheet 29 engages the underside of and is secured to the lateral base flange 8 of the carlines by any suitable means, such as bolts 33 which pass through the flanges and insulating sheets. The lateral base flanges of the carlines illustrated in Figure 6 are not as wide as those of the carlines illustrated in Figures 1 to 5, inclusive, of the drawings so that the insulating sheets 29 may project a relatively great distance beyond their edges. The insulating sheets 28 instead of overlapingly engaging the base flanges of the carlines as heretofore described overlap and are supported by the projecting portions of the insulating sheets 29. Thus in both cases the insulating sheets 28 are supported by the carlines; in Figures 1 to 5, inclusive, being supported directly thereby due 130

to their overlapping engagement with the base flanges of the carlines and in Figure 6, indirectly thereby due to their overlapping engagement with the insulating sheets 29 which are directly carried or supported by the base flanges. In each case, of course, the roof sheets are supported by the carlines through the intermediary of the insulating sheets.

10 From the foregoing it will be perceived that not only does the insulation employed efficiently perform its intended function but that the manner in which it is associated with the carlines and roof sheets eliminates the 15 use of purlins and ridge poles heretofore necessary in flexible roofs of the type herein disclosed. Although a roof of the flexible type has been chosen for illustrating the invention those skilled in the art will readily appreciate 20 that the invention is not limited in its application to this style of roof but that it may be applied equally as well to other types of roofs wherein the roof sheets are associated with the carlines.

25 I claim:

1. In a roof for railway cars, the combination with side plates, of a plurality of carlines connecting said plates, roof sheets respectively associated with and spanning the 30 spaces between the carlines, and sheets of insulating material respectively underlying each of the roof sheets and the carlines, said insulating sheets extending substantially continuously from one side plate to the other, the 35 insulating sheets underlying the carlines projecting beyond the side edges thereof to afford a support for the adjacent insulating sheets underlying the roof sheets.

2. In a flexible roof for railway cars, the 40 combination with a plurality of carlines, of roof sheets respectively associated with and spanning the spaces between the carlines, and insulating material underlying the roof sheets, said insulating material being carried by the carlines and serving to support roof 45 sheets.

3. In a flexible roof for railway cars, the combination with a plurality of roof sheets, of carlines interposed between adjacent 50 sheets, each of said carlines being of substantially channel shape and having laterally projecting flanges, sheets of insulating material respectively underlying the roof sheets and lateral flanges of the carlines, all of said insulating sheets being supported through the intermediary of the carlines, the insulating sheets underlying the roof sheets being relatively rigid and being in supporting engagement with the latter.

60 4. A roof for railway cars comprising a plurality of substantially channel-shaped carlines respectively having laterally projecting flanges, sheets of insulating material respectively secured to said carlines in engagement with the lateral flanges thereof, additional sheets of insulating material respec-

tively extending between the carlines and arranged in overlapping engagement with the lateral flanges of the latter, and roof sheets overlying and supported by said last-named sheets of insulating material. 76

5. A roof for railway cars comprising a plurality of carlines, roof sheets respectively spanning the spaces between the carlines, sheets of insulating material respectively underlying the roof sheets and supported by the carlines, and means connecting the adjoining edges of adjacent roof sheets, said means serving to clamp the insulating sheets between the roof sheets and carlines. 75

6. A roof for railway cars, comprising a plurality of inverted substantially channel-shaped carlines having laterally projecting base flanges, roof sheets associated with and respectively spanning the spaces between the carlines, sheets of insulating material in engagement with the undersides of the roof sheets, said insulating sheets extending between the carlines and arranged in overlapping engagement with the flanges of the latter, additional sheets of insulating material 80 in engagement with the undersides of the lateral flanges of the carlines, and filler members disposed within said carlines to which said last named insulating sheets are secured. 85

7. A flexible car roof for railway cars involving a plurality of carlines, roof sheets spanning the spaces between the carlines, seam caps respectively embracing said carlines and having portions in engagement with adjacent portions of neighboring roof sheets, and sheets of insulating material underlying said roof sheets and affording a support therefor, said insulating sheets being in supporting engagement with the carlines. 95

8. A flexible car roof for railway cars involving a plurality of carlines having laterally projecting base flanges, roof sheets interposed between said carlines, seam caps respectively embracing the latter and having portions in engagement with adjacent portions of neighboring roof relatively rigid sheets, sheets of insulating material underlying said roof sheets and overlappingly engaging the lateral flanges of the carlines, and additional sheets of insulating material 100 underlying the said lateral flanges of the carlines. 110

9. A flexible roof for railway cars, comprising carlines having laterally projecting flanges, roof sheets associated with said carlines for spanning the spaces between them, a sheet of insulating material underlying the lateral flanges of each carline and having portions projecting beyond the side edges thereof, and means for supporting the roof sheets involving relatively rigid sheets of insulating material extending between the carlines and arranged in overlapping engagement with the projecting portions of said first named sheets of insulating material. 115 120 125 130

10. A car roof comprising side plates connected by inverted channel-shaped carlines that are provided with outstanding base flanges, roof sheets supported by said carlines, wooden strips extending longitudinally of said carlines and secured to the base flanges thereof, and an insulating lining extending between the carlines and operatively sustained by the strips to the base flanges thereof.

10 In testimony whereof I affix my signature.
